(57) **CLAIM**

The ornamental design for the reeded bed post, as shown and described.

DESCRIPTION

FIG. 1 is a perspective view of a reeded bed post in accordance with the present invention;

FIG. 2 is a front view of the reeded bed post, the back, left side, and right side all being a mirror image thereof; and,

FIG. 3 is a top view of the reeded bed post, the bottom of the reeded bed post is not illustrated as it forms no part of the present invention.

The broken lines are for environmental purposes only and form no part of the claimed design.
